Inventor

C.F. Kellerman

By *Franklin J. Kellerman* Attorney

UNITED STATES PATENT OFFICE.

CHARLES F. KELLERMAN, OF BATTLE CREEK, MICHIGAN.

TRAFFIC SIGNAL.

Application filed December 1, 1921. Serial No. 519,246.

To all whom it may concern:

Be it known that I, CHARLES F. KELLERMAN, a citizen of the United States, residing at Battle Creek, in the county of Calhoun and State of Michigan, have invented certain new and useful Improvements in Traffic Signals; and I do hereby declare the following to be a full, clear, and exact description of the invention, such as will enable others skilled in the art to which it appertains to make and use the same.

The invention relates to signal means designed most especially for motor vehicles and intended to be applied to the left hand side thereof for indicating a left turn which is at all times attended with a greater or less risk.

The invention provides a signal which may be easily and conveniently manipulated when the curtains are drawn or the vehicle is closed without subjecting the occupants to inclement weather or cold drafts of air.

The invention provides a signal which is operable day or night, being illuminated after dark and clearly observable during the day or night so as to prevent a casualty when making a left turn.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application,

Figure 1 is a side view of a signal embodying the invention, showing the same in operative position and retracted,

Figure 2 is a view similar to Figure 1, the signal being projected,

Figure 3 is a central longitudinal section,

Figure 4 is a transverse section on the line 4—4 of Figure 1, looking to the right,

Figure 5 is a cross section on the line 5—5 of Figure 1, looking to the left,

Figure 6 is a detail view illustrating the cross head of the casing, and

Figure 7 is a detail view of the tube.

Corresponding and like parts are referred to in the following description and desig-

nated in the several views of the drawings by like reference characters.

The signal comprises a tube 1 which may be of any determinate length and diameter. A longitudinal slot 2 is formed in a side of the tube 1 and has its outer end portion 2^a offset ninety degrees whereby to impart a one-quarter turn to the signal when projected. Opposite end portions of the longitudinal slots are connected by means of an inclined slot 2^b which forms in effect a part of the slot. Similar or like clips 3 are provided at opposite ends of the tube 1 and constitute means whereby the signal is adapted to be attached to the windshield or other convenient portion of the vehicle. In the present instance, the clips 3 are designed for attachment of the signal to the windshield 4.

A tube 5 is disposed within the tube 1 and has telescopic connection therewith. A handle 6, connected with the inner tube 5, projects laterally therefrom through the longitudinal slot of the tube 1 and acts jointly with said longitudinal slot to direct the tube 5 when moving longitudinally. A socket 7 is provided at the outer end of the tube 5 and receives a coupling 8 to which a lamp bulb 9 is adapted to be detachably fitted in the usual way. A crosshead 10 is secured to the outer end of the tube 5 and supports a casing 11 which receives the lamp 9. The casing 11 preferably has the form of an arrow so as to indicate direction. The broad sides of the casing 11 are stenciled, the words "Turn left" being cut therein. The narrow sides of the casing are provided with other words or matter such as "Go slow" or "Notice", whereby to attract attention and give warning. Current is conveyed to the lamp bulb 9 by means of the usual electric cord 12 which passes through the inner tube 5 and leads to a suitable source of current supply in any preferred way.

In the practical application of the signal, the same is attached to a convenient part of the vehicle, such as the windshield 4, by means of the clips 3, the casing 11 projecting so as not to interfere with the curtains when drawn or the top when closed. Under normal conditions the tube 5 is telescoped within the tube 1 and the casing 11 is withdrawn so that its narrow sides are disposed forwardly and rearwardly. When the

driver is about to make a left turn, the handle 6 is moved outwardly in the longitudinal slot of the tube 1, thereby projecting the casing 11 and when the latter is near the 5 limit of its outward movement, the handle 6 rides in the inclined portion 2^b of the longitudinal slot and imparts a one-quarter turn to the casing 11 whereby its broad sides face forwardly and rearwardly and expose 10 the words "Turn left" and during the remainder of the outward movement of the tube 5 and casing 11, the handle 6 rides in the short straight portion 2^a of the longitudinal slot and maintains the casing 11 in the 15 adjusted position. After the turn has been made, the tube 5 and casing 11 are withdrawn, the same receiving a one-quarter turn to bring the narrow sides of the casing 11 in forward and rearward position. After dark 20 the circuit containing the lamp 9 is closed so as to illuminate the signal and render the same visible. During the day, the signal is readily visible and the movement thereof when operated, is sufficient to attract attention and give ample warning.

What is claimed is:

1. A signal of the class described comprising a signalling member having corresponding signal characters on opposite sides 30 thereof, means to project and retract the signal member, and said means serving to operate said member to display one set of signal characters when the member is retracted and to display the second set of 35 signal characters when the member is projected.

2. A signal of the class described comprising an inner member, a cross head carried by said inner member, a signal mounted 40 on said cross head, said signal having corresponding signalling characters on opposite faces, a tube receiving the inner member and having offset longitudinal slots in its side, an inclined slot connecting the offset slots, a handle projecting from the inner member through said slots, said handle cooperating with the slots to give the signal member a quarter-turn during the time the handle is traversing the inclined slot 45 and moving longitudinally to project or retract the signal, whereby the signal member displays one set of signals when projected and a second set when retracted.

3. A signal of the class described comprising an inner member, a signal mounted 55 on one end of the inner member, a tube slid-

ably receiving the inner member and having a longitudinally extending slot in one side, supporting eyes having clamps adapted to engage the upper edge of a windshield, 60 and said slotted tube received in the eyes and supported thereby, and a handle secured to said inner member and extending through the slot and said tube.

4. A signal of the class described comprising a signalling member having four sides and having corresponding signalling characters on opposite sides, means to project and retract the signalling member, and means associated with said means to give 65 the signalling member a quarter-turn as it is projected or retracted, whereby it displays one set of signalling characters when in one position and a second set of signalling characters when in its other position.

5. A signal adapted to be arranged transversely of a vehicle with the signalling member normally extending beyond the side of the vehicle and adapted to be projected to extend further beyond the side thereof, the same comprising a signalling member having corresponding signalling characters on opposite sides thereof, means to project and retract the signalling member, and said means serving to operate said signalling member to display one set of signalling characters when in one position and another set of signalling characters when in its other position.

6. A direction indicator for vehicles, the same comprising a signalling member having corresponding signal characters on opposite sides thereof, means to slidably project and retract the signal member, said means moving said signal member in a direction transverse of the vehicle, and said means serving to operate said member to display one set of signal characters when the member is retracted and to display a 95 second set of signal characters when the member is projected, said signal characters being viewable from the front and rear of the vehicle when the member is either in projected or retracted position.

In testimony whereof I affix my signature in presence of two witnesses.

CHARLES F. KELLERMAN.
